[57] CLAIM

The ornamental design for a cabinet bar, substantially as
shown and described.

DESCRIPTION

FIG. 1 is a perspective view of a cabinet bar showing
my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a reduced scale perspective view of FIG. 1,
with the door closed.

*FIG. 1**FIG. 2**FIG. 6**FIG. 7*
